UNITED STATES PATENT OFFICE.

LOUIS ROUANET, OF IVRY-PORT, FRANCE, ASSIGNOR TO COMPAGNIE D'APPLICATIONS
MECANIQUES, OF IVRY-PORT, FRANCE, A FRENCH COMPANY.

HUB CAP.

Application filed March 3, 1927, Serial No. 172,491, and in France March 15, 1926.

The invention has for its object the provision of a stopper-cap arrangement for a motor vehicle wheel, quickly fastened and normally retained into position by an elastic device which is deformed for its setting and its withdrawal. This cap is specially applicable to the removable wheel described in the patent application No. 156,913 dated December 24th, 1926, for "removable wire spoked wheel secured and carried by means of bolts," and can be executed in various ways, the characteristics of which will clearly result from the following description with reference to the accompanying drawing.

In this drawing, showing one embodiment of the invention:

Fig. 1 is a partial sectional view through a wheel provided with a stopper-cap according to the invention.

Fig. 2 shows a rear elevation of the same.

Fig. 3 is a sectional development along the line AA of Fig. 2.

In the arrangement illustrated, the hub member 6 is bent over inwardly on its end portion. A pressed sheet iron cap 7, is provided with two riveted spurs 8, and the flanged portion of the hub member is provided with two openings 9, the outline of which is indicated in dotted lines in Fig. 2. These openings are diametrically opposite each other and each of them comprises a hole, of which the diameter is slightly greater than that of the spur heads 8, extending into an elongated slot of the width of which is smaller than the diameter of these heads and greater than that of the body of these spurs. Two resilient plates 10, secured on the inside face of the flanged portion of the hub 6 as at 10^a (Fig. 2), are provided at their end with a small hole adapted to accommodate the pointed part of a spur head 8 when the stopper is mounted into position.

For the assembly, one has only to press the cap against the front face of the hub, causing the spurs to enter the circular part of the openings 9, a slight rotative movement to the right hand side being then sufficient to lock the stopper in position, the point of each spur head entering the hole

of the corresponding spring 10. To withdraw the cap, reverse operations are performed, a small effort being sufficient to free the spurs from the springs.

To set the cap, it will be sufficient to press said cap against the wheel, to contract the ring and to cause it to enter the groove 14. To withdraw the cap, the extension 16 is depressed, thus enabling the easy withdrawal of the cap by jumping out the ring.

Claims:

1. A stopper cap arrangement comprising a hub member the end portion of which is bent radially, a cup shaped member adapted to encircle and fit the outer periphery of said end portion one of the members being provided with slots, retaining means supported by the other of said members and engaging the slots, and resilient means for preventing the disengagement of said retaining means. 70

2. A stopper cap arrangement comprising a hub member having a flanged end portion, a cup shaped member adapted to bear against said end portion of the hub member, studs on one of the members, the other member being provided with corresponding slots, spurs on the studs and perforated resilient means opposite the slots, whereby accidental disengagement of the cup shaped member is prevented by the engagement of the spurs with the perforations of the resilient means. 80

3. A stopper cap arrangement comprising a hub member the end portion of which is bent radially inward, a cup shaped member adapted to fit the outer periphery of the end portion and to bear against the bent portion of the hub member, studs provided on the cup shaped member, the bent portion of the hub member being provided with corresponding elongated slots, resilient strips secured on the bent portion of the hub member opposite the elongated slots and provided with perforations, and spurs on the studs whereby the cup shaped member is put into position by introducing the studs into the slots and rotating same to engage the spurs into the perforations. 90

LOUIS ROUANET.
